UNITED STATES PATENT OFFICE.

CHARLES P. TURNER AND WILLIAM T. DRAKE, OF HARRISBURG, AND JAMES E. LITTLE, OF STEELTON, PENNSYLVANIA.

DOOR-OPERATING MECHANISM.

1,025,890.

Specification of Letters Patent.

Patented May 7, 1912.

Original application filed October 26, 1910, Serial No. 589,282. Divided and this application filed December 8, 1911. Serial No. 664,641.

To all whom it may concern:

Be it known that we, CHARLES P. TURNER and WILLIAM T. DRAKE, residing at Harrisburg, in the county of Dauphin and State of Pennsylvania, and JAMES E. LITTLE, residing at Steelton, in the county and State aforesaid, have invented certain new and useful Improvements in Door-Operating Mechanism; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to door-operating mechanism for tilting or rocking furnaces that permits the furnace to be rocked or tilted without actuating the door operating mechanism, or permits the door mechanism to be operated to open the door at any position of the furnace, and is a division of our application for patent, filed October 26, 1910, Serial No. 589,282.

Referring to the drawings, in which like parts are similarly designated—Figure 1 is a vertical, central, transverse section of a tilting furnace and the door-operating mechanism. Fig. 2 is a detail side view of the door-operating mechanism.

The tilting furnace F is provided with one or more openings 36, for the introduction of the stock, the examination of the interior of the furnace, etc. Each opening 36 is closed by a door 37 which opens by sliding upward in suitable ways 38 at the sides thereof. The door 37 is provided with a peep-hole 39, and an eye 40, or other equivalent means, to which is fastened a wire rope or chain 50.

The furnace normally stands in the position shown in full lines in Fig. 1. During certain stages of its operation it is desired to roll, rock or tilt it either forward or backward, the two extreme positions being indicated in dotted lines in Fig. 1, and the extreme forward position being the one in which the molten contents of the furnace are discharged through the spout 41.

It may be desirable to operate the door 37 in any position of the furnace, or it more often is the case that the door is not to be

operated during tilting. It is therefore necessary that the door-operating mechanism producing reciprocatory movement of the door be such that this movement be transmitted to the door in practically the same proportion to the motion of the moving mechanism, for any position of the furnace. To this end there is provided a stationary air or hydraulic cylinder 42, fastened to or otherwise supported by a stationary beam or girder 43, independent of the furnace. The lower end of the cylinder is connected to an actuating fluid supply pipe 44, provided with a three-way hand cock 45 within reach of the operator. The cylinder has a piston operating a piston rod 46 which has mounted on its end a cross-head 46^a carrying a rope pulley 47. Below the piston and mounted on the girder or beam 43 are two idle pulleys 48 and 49. A wire rope 50 is connected at one end to the door 37, i. e., 75 fastened in the eye 40, passes over a guide pulley 51 on the furnace frame, partially around the idle pulley 48, thence over pulley 47 and the other idle pulley 49, and is fastened at the other end to an eye 52, bolt, or 80 other equivalent device at the front of the furnace. The cross-head 46^a is connected to one end of a rope 52 that passes over a pulley 53 mounted on the beam or girder 43, so that it will be over the cylinder 42, 85 and the other end of the rope 52 suspends a counterweight 54. Air is admitted by cock 45 through pipe 44 to the cylinder beneath the piston, raises the piston, its rod, cross-head and pulley 47, thereby lengthening the 90 distance between 47 and 48, 49. One end of rope 50 being held fast at 52, the other end connected to the door will be drawn up, and with it the door 37. When the door is to be closed, the cock 45 is turned to vent 95 the cylinder and pipe 44 between the cock and cylinder, to the atmosphere, the weight of the operating parts causing the piston to descend and the door to close. It will thus be seen from an inspection of Fig. 1, 100 that the position of the pulleys 48, 49 with respect to the pulley 51 is such that the sum of the lengths of the portions of the chain or rope 50 between 48 and 52, and 49 and 51 is substantially constant for any position of 105 the furnace, consequently the door may be lifted in any position of the furnace, or the furnace may be tilted without lifting the

door. Any other device may be used in place of the cylinder 42 and its piston, to cause a bodily movement or lifting of the pulley 47.

5 We claim—

1. The combination with a tilting furnace and a vertically sliding door therefor; of mechanism separate from such furnace but flexibly connected to said door to operate 10 it in any position of the furnace.

10 2. The combination with a tilting furnace and a sliding door therefor; of mechanism independent of the furnace permitting the movement of the furnace to any position 15 without actuating the door, and arranged to operate the door in any position of the furnace.

15 3. The combination with a tilting furnace and a sliding door therefor; of stationary 20 mechanism separate from the furnace and flexibly connected to the door, permitting the movement of the furnace to any position without actuating the door and arranged to operate the door in any position 25 of the furnace.

25 4. The combination with a tilting furnace and a sliding door therefor; of a rope connected at one end to the door and at the other end to the furnace, and stationary 30 mechanism between the ends of the rope operating to exert a pull thereon to open the door.

30 5. The combination with a tilting furnace and a sliding door therefor; of a rope con-

nected at one end to the door and at the 35 other end to an opposite corner of the furnace, a stationary cylinder, a piston therein, a pulley carried by the piston, two guide pulleys below the cylinder, said rope passing over said pulleys, and means to supply 40 actuating fluid behind the piston.

6. The combination with a tilting furnace; of door operating mechanism including fluid actuated devices separate from the furnace but flexibly connected to the door and 45 located above the same between its front and rear walls, and a flexible connection between the door and the operating mechanism arranged to permit the furnace to be tilted to any position without operating the door and 50 to operate the door in any position of the furnace.

7. The combination with a tilting furnace; of door operating mechanism above and separate from the furnace, and a flexible 55 connection between the door of the furnace and the furnace, said flexible connection having sliding connection with the operating mechanism.

In testimony that we claim the foregoing 60 as our invention, we have signed our names in presence of two subscribing witnesses.
